HAROLD L. NASH, OF SOUTH NORWALK, CONNECTICUT, ASSIGNOR TO NASH ENGINEERING COMPANY, OF SOUTH NORWALK, CONNECTICUT, A CORPORATION OF CONNECTICUT

HYDROTURBINE PUMPING APPARATUS

Application filed June 1, 1931. Serial No. 541,184.

This invention relates to pumping apparatus of the type in which water or some equivalent liquid is used to produce the pumping action. Such pumps are commonly used to 5 increase the pressure of a volume of air or gas, receiving the air or gas at a lower pressure and discharging it at a higher pressure. These pumps have been found satisfactory 10 and effective for comparatively low pressure work but are not so well adapted to higher pressure ranges.

It is the general object of my invention to improve the construction of hydro-turbine 15 pumping apparatus of this general type, to the end that the apparatus may be made available for substantially increased pressure ranges.

In the accomplishment of this purpose, I 20 preferably remove a portion of the pumping liquid at a certain point in the cycle of pumping operations and restore the liquid at higher pressure at a later point in the pumping cycle. By thus removing a portion of the pumping liquid and thereafter replacing the same by liquid at higher pressure, I am able to effectively discharge the air or gas at a higher pressure than was previously practicable.

My invention further relates to arrangements and combinations of parts which will 25 be hereinafter described and more particularly pointed out in the appended claims.

Preferred forms of my invention are shown 30 in the drawings, in which

Fig. 1 is a sectional elevation of a hydro-turbine pump;

Fig. 2 is a sectional elevation of a similar pump modified to embody my improvements;

Figs. 3 and 4 are partial sectional elevations showing slight modifications of the construction shown in Fig. 2;

Fig. 5 is a sectional elevation of a double lobe pump embodying my improvements, and

Fig. 6 is a sectional elevation showing a slight further modification.

Referring first to Fig. 2, my improved hydro-turbine pump comprises a casing 10 provided with a chamber 11 of non-circular cross section, in which a rotor 12 is mounted on a driving shaft 13 for rotation in the direction 50 of the arrow *a*.

The rotor 12 is provided with a plurality of blades or vanes 15, each of which extends along the rotor between the side walls of the casing 10, with the ends of the blade closely adjacent to said walls. The blades and adjacent side walls thus provide buckets *B*, adapted to be filled with water or liquid *W* contained in the chamber 11.

The chamber 11 is also provided with an inlet port 20 and with an outlet or discharge port 21. A peripheral outlet passage 22 is provided at one point in the cycle of pumping operations, and a similar inlet passage 24 is provided at a later point in the cycle of operations. Any suitable supplementary pumping apparatus may be provided between the passages 22 and 24, such apparatus being indicated diagrammatically at *P* in Fig. 2.

In order to clearly explain the operation of my improved pumping apparatus, it will 70 be convenient to refer to the operation of a usual commercial hydro-turbine pump illustrated in Fig. 1. In this type of pump, a casing 30 encloses a pumping chamber 31, shown as formed with two non-circular lobes, 75 and having inlet ports 32 and outlet ports 33. A rotor 34 is provided with blades 35, coacting with the side walls of the casing to form buckets, all as previously described.

It will be noted that the outer wall of the chamber 31 closely approaches the ends of the blades 35 at the points *A*—*A* in Fig. 1, so that the water or liquid *W* is forced into the buckets at this point and substantially 80 fills the buckets, as indicated at *B*.

Beginning at the inlet ports 32, the casing 30 is gradually enlarged in the direction of rotor movement, allowing the liquid *W* in the full buckets *B*' to move outward as the full buckets pass the inlet ports 32, thus leaving 85 spaces in the bottoms of the buckets in which a partial vacuum is formed. Under these conditions, the air or gas to be pumped flows in through the inlet ports 32 to fill these low pressure spaces. The inner line assumed by the pumping liquid *W* is shown at 36 (Fig. 1).

As the buckets *B* continue to advance, they 90 reach a portion of the casing which is gradually contracted, thus forcing the liquid back 100

into the rotor buckets and forcing the air or gas out of the buckets through the outlet ports 33.

This is the usual operation of this commercial type of hydro-turbine pump, which is commonly double-acting, as shown in Fig. 1.

Let it be now assumed that the lower outlet port 33 in Fig. 1 is closed. We will now have air under compression in the bottom of the bucket B² which is adjacent the closed outlet port and we will also have an amount of liquid at hand which is sufficient to completely fill the bucket B². Consequently there is a surplus of water which is not now needed and which may be removed through a peripheral outlet indicated in dotted lines at 37 in Fig. 1, which corresponds to the outlet passage 22 (Fig. 2) previously described.

The air remaining under compression in the bottom of the successive buckets B² will maintain the water in these successive buckets at the line L in Fig. 2.

If now a new outlet port is provided at a later point in the pumping cycle, as indicated at 21 in Fig. 2, and if liquid under higher pressure is injected into the buckets B² through the inlet passage 24, as the buckets B² approach the discharge port 21, the buckets B² will be substantially filled with liquid under increased pressure and consequently the air or gas in the buckets B² will be forced out through the port 21 under correspondingly increased pressure.

Consequently, by advancing the discharge port to a later point in the pumping cycle, and by removing a portion of the pumping liquid from the pumping chamber and thereafter injecting liquid under increased pressure, I am able to "step-up" or boost the air pressure and to discharge the air or gas against a higher pressure than has been heretofore considered practicable for this type of pump.

Instead of removing the liquid at the point where the discharge port was previously located, as indicated by the pipe 22 in Fig. 2, I may get the same result by positioning the outlet pipe 40 (Fig. 3) at an earlier point in the pumping cycle, correspondingly reducing the radius of the casing at the same point, as indicated at 41. The reduction in cross section of the casing at this point should substantially correspond to the cross section of the outlet passage 40.

I may even go further and locate the outlet passage 44 (Fig. 4) opposite the inlet port 20. In this case, the cross section of the pumping chamber will be reduced throughout the non-circular enlargement thereof by an amount substantially corresponding to the passage 44. In all three forms, Figs. 2, 3 and 4, the water line C will remain substantially in the same location as the water line 36 in Fig. 1.

While I have indicated the passage 22 as

leading to a pump P, and the passage 24 as being supplied by the pump P, it will be understood that it is not necessary to restore the liquid to the casing which was abstracted therefrom, but that the liquid delivered through the passage 24 may be obtained from a storage tank T (Fig. 3) of liquid under pressure, or from any other convenient source of supply. Also the pump P may have a connection 46 (Fig. 2) to an additional source of supply, so that the liquid drawn in through the outlet passage 22 may be supplemented to make up for leakage or other losses.

The advancing of the discharge port 21 in the direction of rotation beyond the previous point of discharge necessitates a greater circumferential space for each pumping cycle than has been previously required. In order to provide this increased circumferential space, I may increase the diameter of the rotor and correspondingly increase the size of the casing, as indicated in Fig. 5, to provide a double-acting or two-lobe pump, or I may somewhat reduce the size of the rotor and casing and provide the single-acting mechanism shown in Fig. 6. In either case, the method of operation is the same as previously described.

A very important advantage of my invention lies in the fact that the air or gas is first placed under a substantial initial pressure by the usual operation of the hydroturbine pump, which pressure is thereafter increased by injecting additional liquid under substantially higher pressure at a point adjacent the discharge port.

Having thus described my invention and the advantages thereof, I do not wish to be limited to the details herein disclosed, otherwise than as set forth in the claims, but what I claim is:—

1. Pumping apparatus comprising a hydro-turbine pump having a pumping chamber of non-circular cross section and provided with inlet and discharge ports, said chamber being peripherally enlarged from a point adjacent the inlet port and being thereafter peripherally contracted toward the discharge port and a rotor mounted in said chamber and having a plurality of displacement chambers, said pump using a liquid for its pumping action, which liquid is rendered effective to partially compress charges of air or gas in said displacement chambers by the velocity of said liquid and the peripheral contraction of the pumping chamber, means providing a discharge passage for a portion of said pumping liquid from the periphery of said pumping chamber at one point in the cycle of pumping operations, and means to restore a similar amount of liquid directly to the periphery of said pumping chamber at a later point in the pumping cycle and at a pressure substantially higher than the nor-

mal pressure of the liquid as removed from the pumping chamber.

2. Pumping apparatus comprising a hydro-turbine pump having a pumping chamber of non-circular cross section and provided with inlet and discharge ports, said chamber being peripherally enlarged from a point adjacent the inlet port and being thereafter peripherally contracted toward the discharge port and a rotor mounted in said chamber and having a plurality of displacement chambers, said pump using a liquid for its pumping action, which liquid is rendered effective to partially compress charges of air or gas in said displacement chambers by the velocity of said liquid and the peripheral contraction of the pumping chamber, an auxiliary pump, an outlet connection from a point in the periphery of said pumping chamber to said auxiliary pump, and an inlet connection from said pump directly into said pumping chamber at a point in the periphery of said pumping chamber adjacent the discharge port of said hydro-turbine pump, said auxiliary pump operating at higher pressure than said hydro-turbine pump.

In testimony whereof I have hereunto affixed my signature.

HAROLD L. NASH.
